Primary Examiner—Susan J. Lucas*Assistant Examiner*—Joel Sincavage*Attorney, Agent, or Firm*—Edward J. DaRin**[57] CLAIM**

The ornamental design for a six volt battery charger, or the like, as shown.

DESCRIPTION

FIG. 1 is a front and upper right perspective view of a six volt battery charger or the like showing our new design. The broken line showing of the six volt battery is included for the purpose of illustrating environmental elements only and forms no part of the claimed design; FIG. 2 is a top plan view of a six volt battery charger or the like shown on a slightly enlarged scale; FIG. 3 is a left side elevational view thereof, the right side elevational view thereof being a mirror image; FIG. 4 is a front elevational view thereof; FIG. 5 is a rear elevational view thereof; and, FIG. 6 is a bottom plan view thereof.

FIG. 2.

FIG. 3.
